UNITED STATES PATENT OFFICE.

MELVIN OVESTRUD, OF STILLWATER, MINNESOTA, ASSIGNOR OF ONE-HALF TO TWIN CITY FORGE & FOUNDRY COMPANY, OF STILLWATER, MINNESOTA, A CORPORATION OF MINNESOTA.

BENDING PRESS FOR TIE-PLATE FLANGES.

Application filed July 26, 1926. Serial No. 124,847.

My invention relates to improvements in presses for bending into jaw forming relation the flanges of tie plate sections of the type comprising a platform member having 5 a perpendicular flange thereon known in common usage as the Barrett tie plate and rail anchor.

An object of the invention resides in providing a press having a frame structure supporting a reciprocable ram carrying a punch block and in further providing an anvil member with an inclined face having a die member pivoted to said anvil in spaced relation thereto, adapted to co-operate with 15 said punch block to bend the flanges of rail plate sections thereover.

A still further object of the invention resides in providing a yoke or freeing member pivoted at one end to said press frame and 20 formed at its other end with a bar having a shoulder thereon movable between said die member and said anvil face, said shoulder being adapted to engage the lower end of a bent tie plate section and free the same from 25 engagement with said die.

A still further object resides in providing hook members pivoted to said ram and adapted to engage the yoke or freeing member upon the upward movement of said ram 30 so as to raise the same and cause the shoulder thereon to free the bent tie plate from the die.

A still further object consists in providing an inclined table arranged in continuation with the face of the anvil, said table having a runway formed therealong adapted 35 to receive unbent tie plate sections and to further provide a slide operating along said runway for feeding the unbent tie plate sections upon said anvil.

A still further object consists in forming a cam on said slide adapted to engage said hook and release said yoke and permit the shouldered bar thereof to return to normal position.

A feature of the invention resides in forming a shield on said slide along the upper portion thereof so as to provide a trough adapted to receive the unbent tie plates while 50 the slide is being moved inwardly towards the anvil, and to further provide a stripper adapted to operate upon tie plates so fed and to cause the same to fall in proper posi-

tion into the runway when the slide is moved into normal position. 55

With the foregoing and other objects in view, which will appear in the following description, the invention resides in the novel combination and arrangement of parts and in the details of construction here- 60 inafter described and claimed.

In the drawings:

Fig. 1 is an end elevational view of a portion of a press embodying one form of my invention. 65

Fig. 2 is a sectional elevational view taken on line 2—2 of Fig. 1.

Fig. 3 is an end elevational view similar to Fig. 1, the feeding mechanism being removed to illustrate the die construction. 70

Fig. 4 is a plan sectional view taken on line 4—4 of Fig. 3.

Fig. 5 is a perspective view of a completed tie plate and rail anchor.

My invention is adapted to operate upon 75 tie plate sections which when formed produce a tie plate and rail anchor such as shown in Fig. 5. These tie plates consist of a platform or body portion 10 punched with suitable spike holes 11 and formed 80 along one edge with an outstanding flange 12 adapted to be bent over to form a jaw, constructed to receive the flange of a rail and securely hold the same attached to the tie plate when said tie plate is spiked to 85 the tie. In the formation of said tie plate a rolled stock is used which is formed with the flange 12 outstanding therefrom, which stock is cut off in suitable lengths and punched with the spike holes. The tie plate 90 sections so formed are run through a furnace and the flanges thereof heated to a sufficient heat to enable the same to be readily bent when inserted into the press. The heated tie sections are then fed into the 95 press forming my invention in which the flanges of the same are bent over to provide the construction shown in Fig. 5 and the tie plate so formed automatically removed from the press.

The press on which the tie plate sections, as illustrated, are formed, consists primarily of a frame indicated in its entirety at A, which comprises a bed 13 and columns 14 and 15 issuing upwardly therefrom. These 105 columns are formed with guideways 16 in

which is mounted a ram 17 adapted to reciprocate in vertical relation to the bed 13. Such structure being well known in the art the operating mechanism of the press has not been shown in detail, though it can readily be comprehended that suitable operating mechanism may be employed for reciprocating the ram 17 in relation to the bed 13 and for tripping the ram when required.

Upon the bed 13, which is formed with the usual waste opening 18 shown in dotted lines in Fig. 3, is mounted an anvil 19, which has attached to it a facing plate 20 having the face thereof arranged in inclined relation to the surface of the bed 13. Facing 20 is preferably arranged at an angle of 60° with the surface of the bed 13 and is attached to the anvil 19 by means of screws 21. The anvil 19 is cast integrally with a base 22 which rests upon the bed 13. Bolts 23 pass through the base 22 and are adapted to be screwed into the bed 13 for firmly holding the anvil mounted thereon. To brace against the side thrust encountered in the operation of the invention a backing block 24 is employed which is situated behind the anvil 19 and rests upon the base 22 and against the inner face of column 15. This backing block serves to steady the anvil and at the same time insures the accuracy of the machine in operating upon the tie plate sections.

Along the lower portion of the anvil 19 is formed two depending arms or spaced lugs 25 which are bored to receive a transversely disposed shaft 26. These lugs and said shaft are disposed within the waste opening 18 situated in the middle of the bed 13, though it can readily be comprehended that, if desired, the entire anvil structure may be sufficiently elevated to bring the same above the face of the bed when the press is constructed with sufficient clearance between the ram and the bed. In conjunction with the anvil 19 I employ a mounting 27 which is formed with a depending ear 28 adapted to extend between the arms 25 and to be pivoted upon the shaft 26. This mounting is formed along the upper portion thereof with a rabbet 29 adapted to receive a tool-steel forming and spacing die 31 which is detachably secured therein by means of suitable bolts 30. It will be noted that the face of said forming die is flush with the face of the mounting 27 and that the same are so arranged as to lie parallel with the face of the anvil 19. In feeding the tie plate sections to the machine, the same are fed with the standing flange 12 thereof resting upon the upper edge of the die member 31 as clearly shown in Fig. 3, the body of said tie plate being positioned between the said die member and the facing plate 20 of anvil 19. It can readily be seen that upon mo-

ment of the mounting 27 toward the anvil 19 that the tie plate section to be bent may be rigidly clamped therebetween and so held as to permit the bending of the flange about the upper portion of the spacing die 31.

Directly attached to the ram 17, which is formed with a dove-tailed slot 32 for this purpose, is a punch block 33 held in place within said slot by means of a wedge 34. This punch block is formed with die faces 35, 36 and 37 conforming to the surface of the finished tie plate resting upon the anvil 19, the surface 37 engaging the extreme end of the flange 12 and bending the same over the die member 31 as the ram 17 descends in its guideways 16.

In bending the flange of the tie plate over the forming spacing die the same is caused to tightly clamp about said die and to cling thereto, thus preventing the ready removal thereof. For freeing the bent tie plate section from the die member 31, I employ a structure best illustrated in Figs. 3 and 4. This structure consists of a yoke indicated in its entirety at B which consists of two spaced parallel arms 38 and 39 offset at 40 and 41. These arms are connected together at one end by means of a cross bar 42 and near their centers by means of a brace 43. The bar 42 extends outwardly beyond the offset portion 40 of arms 38 as indicated at 44 for a purpose to be presently described. The extreme ends of the arms 38 and 39 are journaled to a shaft 45 which is mounted in a bracket 46 secured to the outer portion of column 14 by means of bolts 47. Cotter pins 48 passing through the ends of the shaft 45 hold the same in proper relation to the yoke B so that the same may function in the desired manner. It will be noted that the yoke B slopes downwardly toward the anvil 19, the bar 42 lying between the mounting 27 and the anvil 19, said mounting and anvil being recessed at 49 and 50 for the reception of the same. The arms 38 and 39 straddle the column 14 while the offset portions 40 and 41 thereof straddle the mounting 27, said parts being arranged to permit the yoke to travel upwardly a sufficient distance to free the bent rail section from the die member 31 as will presently become apparent. The bar 42 where it extends over the arms 25 of anvil 19 is formed of lesser depth than throughout the remainder of its extent for the purpose of permitting the same to clear the upper portion thereof. Said bar 42 is further formed with a shoulder 51 which lies immediately beneath the lower edge of the body portion 10 of the tie plate when the same is properly positioned as indicated. This shoulder is adapted to engage said edge of the tie plate and serves to free the same from engagement with the forming and spacing die 31 when

said yoke B is swung upwardly upon the shaft 45.

For operating the yoke B a shaft 52 is employed which extends directly through the head proper of the ram 17. This shaft has attached to it at its two extreme ends two depending hooks 53 and 54 which are rigidly secured to said shaft by means of keys 55 and clamp bolts 56. To hold said shaft 52 from longitudinal movement two collars 73 and 74 are employed which are rigidly secured thereto by means of set screws 75. These hooks, at their lower extremities, are provided with catches 57 adapted to engage beneath latch lugs 58 attached to the yoke B. These latch lugs, which are preferably constructed of tool steel, are mounted between forked protrusions 59 formed on the offset portions 40 and 41 of the yoke arms 38 and 39 and are held in place therebetween by means of bolts 60. In operation the yoke B, through its own weight, drops until the central portion of the yoke bar 42 engages the upper surface of the arms 25, the position of the same being illustrated in Fig. 3. Upon the ram 17 descending, the punch block 33 operates to bend the flange of the tie plate as previously described and the hooks 23 descend along with said ram. When the ram reaches its lowermost position, the catches 57 on hooks 53 engage beneath the protruding portions of the latch lugs 58, said yoke B being thereby caused to be swung upwardly as the ram 17 ascends. During such upward movement of the ram 17, the shoulder 51 on the bar 42 is caused to engage the lower edge of the body portion of the formed tie plate and to free the same from engagement with the spacing die 31. When the ram 17 reaches its uppermost position (Fig. 1), the yoke B holds the tie plate elevated and free from the spacing die 31.

For causing the catches 57 to engage the latch members 58 and to hold the yoke B in elevated position, I employ the following construction, best shown in Figs. 1 and 3. A lug 61 is formed on the hook member 53 and drilled to freely receive a bolt 62 passing upwardly therethrough. Bolt 62 is threaded into a bracket 63 attached to the ram 17 by means of bolts 64. Upon the bolt 62 is mounted a compression coil spring 65 which is seated at one end against the lug 61 and at its other end against a nut 66 mounted upon said bolt. Lock nuts 67 and 68 hold the nut 66 and the bolt 62 in adjusted position. The spring 65 yieldingly holds the lug 61 against the head of bolt 62, thus normally disposing the hooks 53 in the position shown in Fig. 3. As the ram 17 descends the curved portions of the catches 57 and the latch lugs 58 contact causing the hooks 53 to swing in opposition to the spring 65 until said catches and latch lugs pass each other

when said hooks fall back to normal position, engaging said latch lugs and causing the yoke B to be moved as previously described.

The mounting 27 and the die member 31 attached thereto are caused to clamp the tie plate by means of a bent lever 67 which is secured to said mounting 27 by means of bolts 68. This lever extends outwardly to the side of the press and upwardly along the same where said lever terminates in an inclined portion 69 lying in proximity to the shaft 52 and adapted to be engaged by a sleeve 70 mounted on said shaft, when the ram approaches its uppermost position. A coil spring 71 is attached at one end to the extreme end of the inclined portion 69 of said lever and at its other end to a bolt 72 screwed into the guide member 16 of column 15. This spring acts to swing the mounting 27 and the die 31 upon the shaft 26 and cause the same to move toward the facing plate 21 of anvil 19 and rigidly clamp the tie plate mounted therebetween. The inclined portion 69 of said lever is so constructed that when the same is engaged by the sleeve 70 said lever is forced outwardly in opposition to the spring 71 to release the clamping action of said mounting and facing die and to permit of the insertion of an unbent tie plate therebetween and after the removal of the bent tie plate. As will be noted in Fig. 2, the sleeve 70 is situated between the hook 54 and the collar 74 mounted on said shaft 52, so that the inclined portion 69 of lever 67 becomes guided between the hub of hook 54 and said collar 74. By substituting sleeves of different diameters in place of the sleeve 70, the opening of the spacing die and mounting can be adjusted at will.

The tie plate sections are fed into the machine as follows: At the side of the press is arranged a table C which is positioned in inclined relation and formed in continuation of the inclined face of anvil 19. This table is formed with lugs 77 by means of which the same may be bolted to the anvil 19 with cap screws 78, and is further formed with a lug 79 permitting the attachment of the outboard end of said table to a leg 80 independent of the framework A of the press. At the lower portion of table C the same is formed with an outstanding flange 81. (Fig. 1), which has attached to it a T flange spaced from and parallel to the surface of said table to provide a groove or runway 83. Above this runway is formed another groove 84. This groove communicates with a slot 85 extending along the table C through a portion of the length thereof. A slide 86 of a width equal substantially to that of the tie plate to be fed through the machine is slidably positioned upon the table C. The lower portion of said slide 86 rides within the runway 83, the upper portion thereof

105

110

115

120

125

130

being formed with a T flange 87, which rides within the slot 84. This slide is held in position upon the table C by means of a screw 88 which passes through the slot 85 and is screwed into the T flange 87 thereof. A handle 89 is attached to the extreme end of the slide 86 and extends along the same toward the inner end thereof, said handle serving as a means by which the slide may be manually reciprocated along the runway 83 and groove 84.

Adjacent the anvil 19 I provide a chute 90 which leads up to and is connected with the upper portion of the table C. This chute has side walls 91 and 92 and serves to convey the heated tie plates upon the table C. As the tie plates are discharged from chute 90 the same slide down table C until the lower edges of the body portion thereof become lodged within the extreme end of the runway 83, as shown in dotted lines at 95 in Fig. 2. By now forcing the slide 86 inwardly the end 93 thereof is caused to engage the tie plate so positioned and to cause the same to be slid along said runway and into the space between the mounting 27 and the anvil 19. The runway 83 is so situated in relation to the bar 42 of the yoke B that the bottom of the tie plate is always situated above the shoulder 51 and so that the flange 12 of the tie plate comes above the upper edge of the spacing die 31. This permits the tie plate to be properly inserted between the anvil and spacing die so that the same may be operated upon as previously described. Where there has been a previous tie plate bent in the machine, the edge of the incoming tie plate engages the edge of the bent tie plate and causes the latter to be ejected from the machine, said unbent tie plate then taking the position of the previous bent tie plate.

Where a continuous run of tie plates occurs provision has been made to automatically hold back the following tie plates in chute 90 while a particular tie plate is being fed into the machine. This is accomplished by providing a shield 94 which issues upwardly from the T flange 87 of slide 86 and runs outwardly from the table C. When the slide 86 has been slid inwardly this shield becomes positioned directly in front of the chute 90 so that the next following tie plate upon being released by the removal of the lowest tie plate will fall directly into the trough formed between said shield and the table C, where the same will lie as long as the slide remains in its inner position. Upon moving the slide 86 outwardly to its position as shown in Fig. 2, the side wall 91 of chute 90, which extends downwardly along table C, serves as a tripper and causes such tie plate to become disengaged from the trough formed by shield 94 and the flange 87, permitting the tie plate to drop

into position in the runway 83 as soon as the slide has been completely withdrawn. It will be hence readily comprehended that tie plates may be successively fed into the press by the manual reciprocation of slide 86 so that the manual handling of the tie plates with tongs is eliminated.

For releasing the yoke B and permitting the same to return to normal position, the handle 89 attached to slide 86 is formed with a cam 95 best shown in Fig. 4. This cam is situated in proximity to the lowermost portion of hook 53 and is adapted to engage the same and throw said hook outwardly in opposition to spring 65 so as to cause the catch 57 to become disengaged from the latch lug 58. Both the hooks 53 and 54 being keyed upon shaft 52 operate simultaneously and hence become disengaged from the latch lugs 58 at the same time. Cam 95 is designed to release yoke B as soon as the completed tie plate has been removed from the machine. This cam may be adjusted by means of a stud bolt 96 which is secured at one end to the slide 86 and which passes through the handle 89 near the cam member 95 thereon. Nuts 97 and 98 on said bolt on each side of handle 89 are for the purpose of adjusting the cam 95 which contacts with the hook member 53.

In summarizing, the operation of the machine is as follows: The heated tie plates are fed upon the table C by means of the trough 90 where the same drop into the runway 83. By sliding the slide 86 inwardly the forward edge 93 thereof engages the tie plate and moves the same into the space between the anvil 19 and the mounting 27, the flange of the tie plate resting upon the upper edge of the die member 31. At the same time a succeeding tie plate drops into the trough formed by the shield 94 on table C, where the same remains until the slide is manually returned to normal position. During such return movement of the slide 86, the side wall 91 of chute 90, serving as a stripper, holds the succeeding tie plate back permitting the same to drop in place in the runway 83 only when said slide has been fully retracted. Upon manually operating the tripping mechanism (not shown) of the press, the ram 17 is caused to descend. As soon as the sleeve 70 on shaft 52 leaves the inclined portion 69 of lever 67, spring 71 causes the mounting 27 and the die plate 31 to securely clamp the body portion of the tie plate against the facing plate 20 of anvil 19. When the punch block 33 strikes the flange 12 of the tie plate, the same is bent over and upon the forming and spacing die 31 so as to provide the finished product. The catches 57 of hooks 53 and 54 slip beneath the latch lugs 58 when the ram reaches its lowermost position. As the ram 17 ascends, catches 57 engage the latch lugs 58 and cause the

- yoke B to rise, bringing the shoulder 51 of bar 42 in contact with the lower edge of the body portion of the tie plate and freeing the same from the die member 31. As the 5 ram reaches its uppermost position sleeve 70 engages the inclined portion 69 of lever 67 and withdraws the mounting 27 from its clamping position upon the tie plate. The hooks 53 and 54 maintain the yoke B in 10 elevated position and consequently hold the tie plate free from the spacing die until the operator has had the opportunity to manually shift the slide 86 and eject the bent tie plate from the machine and feed an unbent 15 one into the same. As the bent tie plate leaves the machine cam 95 engages the hook 53 and releases the yoke B which again resumes its normal position and completes the cycle of operation of the machine.
- 20 The advantages of my invention are manifest. Tie plates may be automatically fed and ejected from the machine without the manual handling of the same which in the case of heated structures is both awkward and inconvenient. The machine may be 25 made to function as rapidly or as slowly as desired, and the same is so arranged as not to choke when the machine is stopped for any purpose. The various operating elements 30 of the invention are readily accessible for inspection and repairs and may be conveniently removed and replaced whenever the occasion requires. Those portions of the device subject to greatest wear are formed 35 of tool-steel or other suitable metal and may be removed and replaced as required. The parts are so arranged and constructed as to operate in a positive and effective manner so as to cause the machine to function without interruption.
- 40 Changes in the specific form of my invention, as herein disclosed, may be made within the scope of what is claimed without departing from the spirit of my invention.
- 45 Having described my invention, what I claim as new and desire to protect by Letters Patent is:
1. A press for bending the flanges of tie plate sections, comprising a frame, a reciprocable ram carried by said frame, a die member mounted on said frame, a bending punch on said ram co-operating with said die member for bending the flange of the tie plate section thereover, means operated by said ram for freeing the bent tie plate section from said die and for so holding it, means for removing the bent tie plate section from the press and means operated by said removing means for releasing said freeing and holding means.
- 50 2. A press for bending the flanges of tie plate sections, comprising a frame, a reciprocable ram carried by said frame, a die member mounted on said frame, a bending punch on said ram co-operating with said die member for bending the flange of the tie plate section thereover, a member pivoted to said frame having a shoulder normally positioned in proximity to said die for engaging a tie plate section, means carried by said 55 ram for moving said pivoted member to free the bent tie plate section from said die and for so holding it, means for removing the bent tie plate section from the press and means operated by said removing means for releasing said freeing and holding means to permit said member to return to normal position.
3. A press for bending the flanges of tie plate sections, comprising a frame, a reciprocable ram carried by said frame, a die member mounted on said frame, a bending punch on said ram co-operating with said die member for bending the flange of the tie plate section thereover, a member pivoted to said frame having a shoulder normally positioned in proximity to said die for engaging a tie plate section, a hook pivoted to said ram adapted to engage said pivoted member for raising the same and freeing the bent tie 60 plate section from said die, said hook holding said member in raised position throughout the upper stroke of said ram, a slide for removing said bent tie plate section from the press, and means actuated by said slide for releasing said hook from said member.
4. A press for bending the flanges of tie plate sections, comprising a frame, a reciprocable ram carried by said frame, a die member mounted on said frame, a bending punch on said ram co-operating with said die member for bending the flange of the tie plate section thereover, a member pivoted to said frame having a shoulder normally positioned in proximity to said die for engagement with a tie plate section, a hook pivoted to said ram adapted to engage said pivoted member for raising the same and freeing the bent tie plate section from said die, said hook holding said member in raised 65 position throughout the upper stroke of said ram, a slide for removing said bent tie plate section from the press, and a cam member on said slide adapted to engage said hook for releasing the same from engagement with said member.
5. A press for bending the flanges of tie plate sections comprising a frame, a reciprocable ram carried by said frame, an anvil member and a jaw member movable relative 70 to one another and supported on said frame for clamping the body portion of a tie plate section therebetween, one of said members having a spacing die mounted thereon, a bending punch on said ram co-operating with said die member for bending the flange of the tie plate section thereover, a member pivoted to said frame having a shoulder formed thereon movable between said anvil and jaw member and adapted to engage a tie 75

plate section mounted between said anvil and jaw member, means operated by said ram for moving said pivoted member along the face of said die for freeing the bent tie plate section from said die and for so holding it, and means for removing said bent tie plate section from the press.

6. A press for bending the flanges of tie plate sections comprising a frame, a reciprocable ram carried by said frame, an anvil member and a jaw member movable relative to one another and supported on said frame for clamping the body portion of a tie plate section therebetween, one of said members having a spacing die mounted thereon, a bending punch on said ram co-operating with said die member for bending the flange of the tie plate section thereover, a member pivoted to said frame having a shoulder formed thereon movable between said anvil and jaw member and adapted to engage a tie plate section mounted between said anvil and jaw member, and means operated by said ram for moving said pivoted member along the face of said die for freeing the bent tie plate section from said die and for so holding it, means for removing said bent tie plate section from the press, and means operated by said removing means for disengaging said operated means and releasing said member.

7. A press for bending the flanges of tie plate sections comprising a frame, including a bed and spaced columns issuing upwardly therefrom, a ram reciprocable along said columns, an anvil member mounted on said bed having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie plate section therebetween, a bending punch on said ram adapted to co-operate with said die for bending the flange of said tie plate section thereover, and means formed on said ram for engaging said yoke and raising the same to free the bent tie plate section from said die member.

8. A press for bending the flanges of tie plate sections comprising a frame, including a bed and spaced columns issuing upwardly therefrom, a ram reciprocable along said columns, an anvil member mounted on said bed having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie

plate section therebetween, a bending punch on said ram adapted to co-operate with said die for bending the flange of said tie plate section thereover, a hook pivoted to said ram and adapted to engage said yoke for elevating the same and causing the bent tie plate section to be freed from said die member.

9. A press for bending the flanges of tie plate sections comprising a frame, including a bed and spaced columns issuing upwardly therefrom, a ram reciprocable along said columns, an anvil member mounted on said bed having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie plate section therebetween, a bending punch on said ram adapted to co-operate with said die for bending the flange of said tie plate section thereover, a hook pivoted to said ram and adapted to engage said yoke for elevating the same and causing the bent tie plate section to be freed from said die member, a slide for removing the freed tie plate section from the press and a cam carried by said slide for engagement with said hook to release said yoke upon the removal of the formed tie plate section from the press.

10. A press for bending the flanges of tie plate sections comprising a frame, including a bed and spaced columns issuing upwardly therefrom, a ram reciprocable along said columns, an anvil member mounted on said bed having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie plate section therebetween, a bending punch on said ram adapted to co-operate with said die for bending the flange of said tie plate section thereover, a table continuous with the face of said anvil, a guideway formed along said table, a slide movable along said guideway, means for conveying tie plate sections upon the face of said table adjacent said anvil, said slide being adapted to engage said tie plate sections and feed the same upon said anvil.

11. A press for bending the flanges of tie plate sections comprising a frame, including a bed and spaced columns issuing upwardly therefrom, a ram reciprocable along said columns, an anvil member mounted on said bed

- having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie plate section therebetween, a bending punch on said ram adapted to co-operate with said die for bending the flange of said tie plate section thereover, a guide plate continuous with the face of said anvil, a runway formed on the lower edge of said guide plate being situated parallel with the shoulder of said yoke and above the uppermost position thereof, means for feeding tie plates upon said guide plate adjacent said anvil and into said runway, a slide movable along said runway, and adapted to engage the edge of the tie plate and move the same upon said anvil.
12. A press for bending the flanges of tie plate sections comprising a frame, including a bed and spaced columns issuing upwardly therefrom, a ram reciprocable along said columns, an anvil member mounted on said bed having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie plate section therebetween, a bending punch on said ram adapted to co-operate with said die for bending the flange of said tie plate section thereover, a guide plate continuous with the face of said anvil, a runway formed on the lower edge of said guide plate being situated parallel with the shoulder of said yoke and above the uppermost position thereof, means for feeding tie plates upon said guide plate adjacent said anvil and into said runway, a slide movable along said runway, and adapted to engage the edge of the tie plate and move the same upon said anvil, a hook pivoted to said ram and adapted to engage said yoke and raise the same to cause the shoulder of said bar to engage the end of the bent tie plate and free the same from said die, the edge of an unbent tie plate engaging the end of the bent tie plate and serving to remove the same from the press upon movement of said slide, and a cam on said slide co-operating with said hook for releasing the same from said yoke and permitting the yoke to return to normal position.
13. A press for bending the flanges of tie plate sections comprising a frame, including a bed and spaced columns issuing upwardly therefrom, a ram reciprocable along said columns, an anvil member mounted on said bed having an inclined face, a die member pivoted to said anvil in spaced relation to said inclined anvil face, a yoke straddling one of said columns and pivoted at one end thereto, said yoke having a bar providing a shoulder formed along the other end thereof, said bar being movable between said anvil face and die member, said anvil and die member being adapted to receive a tie plate section therebetween, a bending punch on said ram adapted to co-operate with said die for bending the flange of said tie plate section thereover, a guide plate continuous with the face of said anvil, a runway formed on the lower edge of said guide plate being situated parallel with the shoulder of said yoke and above the uppermost position thereof, means for feeding tie plates upon said guide plate adjacent said anvil and into said runway, a slide movable along said runway, and adapted to engage the edge of the tie plate and move the same upon said anvil, a shield formed on said slide along the upper portion thereof to provide a trough adapted to receive tie plate sections when said slide is in its innermost position, and a stripper for removing a tie plate section from within said trough and causing it to descend into feeding position upon said runway.

In testimony whereof, I have signed my name to this specification.

MELVIN OVESTRUUD.
